UNITED STATES PATENT OFFICE

THOMAS A. CREIGHTON, OF VENTURA, CALIFORNIA

BLOW-OUT PREVENTER

Application filed June 2, 1926. Serial No. 113,296.

This invention relates to blow-out preventers for use in oil wells or other types of wells where it is desired to prevent blow-outs with disastrous results to tubing and other 5 well mechanism due to excessive gas pressure within the well, or in case the drilling should lead into oil sands which would cause a gusher.

The invention has for an object the novel 10 and useful provision, formation, construction and association and relative arrangements of members which will effectively prevent gas blow-outs in wells, which is positive in its operation, easy to handle and inexpensive to manufacture.

A still further object is to provide a blow-out preventer which may be quickly assembled for use without threading the parts thereof over the tubing, kelly or the like. 20 Other objects, advantages and features of invention may appear from the accompanying drawing, the subjoined detailed description and the appended claims.

In the drawing: 25 Fig. 1 is a fragmentary longitudinal sectional view of my invention in operative position.

Fig. 2 is a plan view of the pressure ring. 30 Fig. 3, is a bottom plan view of the same. Fig. 4, is a sectional view taken on line 4—4 Fig. 2.

Fig. 5, is a plan view of a modified form of ring.

In practicing the invention I may incorporate the device with the drill stem of a rotary outfit and the drill stem, as is usual, projects through the spider of a turn-table, said drill stem being held in position by the usual slip members within the spider. 35 Beneath the rotary turn-table and associated with the casing is a bowl member. In case of accident or any indication that a gusher is about to be produced, the slip might be lifted from the spider of the rotary turn-table, the drill stem lifted and the members of the mechanism dropped within the bowl associated with the casing, and which members tend to seal the bowl so that gas or oil would not escape therefrom, and hence could 40 not escape from the casing. The mechanism 45

referred to consists of an upper or pressure and lower or seating ring with a gasket member formed of some pliable or expansible material interposed between the upper and lower annulus members. The upper annulus is 55 formed to receive a slip member so that the said annulus and the drill stem may be locked in a given position. The gasket and lower annulus will drop within the bowl associated with the casing when the slips and the spider are removed from the turn table, and a lowering of the drill stem will allow the upper ring to contact with the packing or gasket and the weight of the drill stem being transferred to the upper ring will cause said ring 60 to bear upon the gasket and "mash" the same against the drill stem and against a portion of the inner surface of the bowl member. The lower ring being formed of metal will 65 act as a buffer so that the gas will not come into actual contact with the gasket. This is a precautionary measure so that if gas should escape it would be unable to cut away the gasket. It is thus evident that in order 70 to blow out the well it would be necessary to lift the entire drilling string. It is thus evident that I have produced a simple means for effectively preventing blow-outs such as are liable to occur in well practice with particular 75 application to oil wells.

Referring more particularly to the drawing: my blow-out preventer cooperates with the rotary drill pipe 1, sometimes called the kelly and which is square in cross section. The drill pipe enters the usual casing 2, on 80 the top of which my blow-out preventer 3 is mounted.

The blow-out preventer comprises a shell 4 secured to the top of the casing 2 by a sleeve 5 threaded onto the shell and casing. A seat 6 is formed in said shell upon which the lower or seating ring 7 rests. This ring is provided with a central square opening 8 through which the kelly 1 extends. An annular flange 9 projects from the upper surface of the ring 7, 85 which flange extends into a recess 10 formed on the packing ring 11. The packing ring 11 fits the shell 4 and is adapted to be pressed against the wall of said shell and against the kelly 1 to prevent the escape of oil or gas. 90 95 100

An upper or pressure ring 12 fits into the sleeve 4 and an annular ring 13 depends from the lower surface thereof, which cooperates with a groove 14 in the packing 11 to press said packing against the sleeve and kelly when pressure is applied to said ring. A central square opening 15 is provided in the ring 12 through which the kelly 1 extends and the walls of the opening are tapered as 10 at 16 to accommodate slips 17 the teeth of which slips bite into the kelly and thus causes the ring to support the weight of the drilling string.

In assembling the ring 12 about the kelly; 15 which is frequently necessary, much time is lost and the threads of the kelly are damaged by threading the ring thereon. I have provided a means, whereby the ring 12 can be assembled at any point on the kelly, comprising a block 18 which fits into a slot 19 cut through said ring into the opening 15, and of the same width as said opening; so that the kelly can pass there-through. The walls of said slot and the sides of the block 25 are tapered to provide a seat for said block. Dovetail notches 20 are provided in the ring 12 and ears 21 on the block 18 enter said notches thereby holding the block in position and preventing it from sliding out. It 30 will be seen that the inner edge of the block 18 forms one side of the opening 15, and removal of the block will enable the ring to be quickly removed from the kelly.

In Fig. 5 I have shown a modified form 35 of ring in which the ring 12' is made in two pieces 22, 23. The piece 23 has dovetail notches 24, in which lugs 25 on the piece 22, fit.

Assuming that the rotary is in operation 40 and drilling is progressing, and it is noticed by the driller that mud flowing in the sump has an effervescent appearance indicating gas pressure, if the operator determines that the gas pressure is liable to become serious he stops the operation of the 45 rotary, raises the drill stem 1 through the medium of the draw-works of the rotary, and inserts a slip or slips 17 within the beveled portion 16 of the member 12 so that the teeth of such slips bite against the sides 50 of the drill stem 1. The drill stem is lifted sufficiently to lift the drill from the bottom of the well hole and a sufficient distance so that upon a lowering of the drill tubing the 55 same will not again contact with the bottom of the well hole when the blow-out preventer is in position. After the slips 17 are placed within the member 12 said member will be held to the stem 1, where- 60 upon the drill stem with its connected pipe may be lowered in the well hole where the ring 12 will contact with the gasket 11, whereupon the entire load, that is the weight of the drill stem and the pipe associated 65 therewith, will be carried by the members 11,

12 and 7 and the shell 4. The weight of all this drilling mechanism will of course compress the gasket 11 and force the periphery thereof against a portion of the inner surface of the bowl and likewise force the gasket against the surface of the drill stem 1, thus making an air-tight fit. 70

The slips 17, are not placed in position until such a time as it is desired to pack off the casing, that is, the kelly rotates freely to drill the well, and is, of course, fed downwardly constantly during this operation and when the casing pressure indicates that a blow-out might occur, the slips 17 are inserted, and the weight of the tool string is permitted to rest upon the rings 7, 12 and the packing 11, and thus begin packing off the casing; but as previously stated, during the drilling operation, the slips are not in position and consequently the kelly or square 80 drill stem is not connected in any way to the ring 12, and thus the rotation of the drill stem is not interfered with. 85

Having described my invention I claim:

1. The combination with a drill pipe and 90 well casing of a shell associated with the casing, a seat in said shell, a lower ring positioned on said seat, an upper ring, a packing member positioned between said upper and lower rings, said upper and lower rings and packing member having central openings therethrough, through which the drill pipe extends, said upper ring having a slot cut therethrough communicating with the central opening, a block adapted to fit in said slot 100 and means to lock said block in position, and removable means connecting said upper ring and drill pipe whereby the weight of the drill pipe is exerted to compress the packing member. 105

2. The combination with a drill pipe and well casing of a shell associated with the casing, a seat in said shell, a lower ring positioned on said seat, an upper ring, a packing member positioned between said upper and lower rings, said upper and lower rings and packing member having central openings therethrough through which the drill pipe extends, said upper ring having a slot cut therethrough communicating with the central opening, a block adapted to fit in said slot, said upper ring having notches cut therein, lugs on said block adapted to enter said notches whereby the block is locked in position, and slips adapted to fit into said upper ring and engage the kelly whereby the weight of the drill pipe serves to compress the packing member. 115

3. The combination with a drill pipe and well casing, of a shell associated with the 125 casing, a seat in said shell, a lower ring positioned on said seat, an upper ring, a packing member positioned between said upper and lower rings, said upper and lower rings and packing member having central openings 130

therethrough, through which the drill pipe extends, said upper ring having a slot cut therethrough communicating with the central openings, a block adapted to fit in said slot, said upper ring having notches cut therein, lugs on said block adapted to enter said notches whereby the block is locked in position, the walls of said slot and block being tapered to provide a seat for the block, and 10 annular rings projecting from the upper and lower rings adapted to engage the packing to force said packing against the shell and drill pipe.

In testimony whereof I affix my signature.
